Primary Examiner—Philip S. Hyder
Attorney, Agent, or Firm—Harness, Dickey & Pierce, P.L.C.[57] **CLAIM**

The ornamental design for a tool container, as shown and described.

DESCRIPTION

FIG. 1 is a front perspective view of a container in accordance with the present invention.

FIG. 2 is a rear perspective view of a container in accordance with the present invention;

FIG. 3 is a front elevation view of FIG. 1;

FIG. 4 is a rear elevation view of FIG. 1;

FIG. 5 is a left elevation side view of FIG. 1;

FIG. 6 is a right elevation side view of FIG. 1;

FIG. 7 is a bottom plan view of FIG. 1; and,

FIG. 8 is a top plan view of FIG. 1.

[57] CLAIM

The ornamental design for a tool container, as shown and described.

DESCRIPTION

FIG. 1 is a front perspective view of a container in accordance with the present invention.

FIG. 2 is a rear perspective view of a container in accordance with the present invention;

FIG. 3 is a front elevation view of FIG. 1;

FIG. 4 is a rear elevation view of FIG. 1;

FIG. 5 is a left elevation side view of FIG. 1;

FIG. 6 is a right elevation side view of FIG. 1;

FIG. 7 is a bottom plan view of FIG. 1; and,

FIG. 8 is a top plan view of FIG. 1.
